United States Patent

Des. 234,477
Patented Mar. 18, 1975

234,477

STOOL

William F. Lockhardt, Jr., Durham, Alfred M. Norton, Jr., Nashua, Dana P. Powers, Amherst, and Richard J. Norton, Nashua, N.H., assignors to The Maine Manufacturing Company, Nashua, N.H.

Filed Apr. 23, 1973, Ser. No. 353,798

Term of patent 14 years

Int. Cl. D6—01

U.S. Cl. D6—36

Fig. 1.

Fig. 2.

Fig. 3.

FIG. 1 is a front, top and left side perspective view of a stool showing our new design;

FIG. 2 is a front and bottom perspective view; and

FIG. 3 is a right side elevational view with the lid in a slightly raised position.

The configuration of the bottom of the lid is the same as the bottom of the stool.

We claim:

The ornamental design for a stool, as shown and described.
